UNITED STATES PATENT OFFICE.

SAMUEL YEANEY STOCKAMORE, OF GLOVERSVILLE, NEW YORK.

WELT-CUTTING MACHINE.

SPECIFICATION forming part of Letters Patent No. 760,579, dated May 24, 1904.

Application filed January 7, 1904. Serial No. 188,112. (No model.)

To all whom it may concern:

Be it known that I, SAMUEL YEANEY STOCKAMORE, a citizen of the United States, residing at Gloversville, in the county of Fulton and 5 State of New York, have invented certain new and useful Improvements in Welt-Cutting Machines; and I do declare the following to be a full, clear, and exact description of the invention, such as will enable others skilled in the 10 art to which it appertains to make and use the same.

This invention relates to improvements in machines for cutting leather or other material into welts or strips for use in the manufacture 15 of gloves, mittens, pocket-books, and other leather goods.

The object of the present invention is to provide a machine of this character which will be simple in construction, durable in use, effi- 20 cient in operation, and comparatively inexpensive to produce.

With this and other objects in view the invention consists of certain novel features of construction, combination, and arrangement 25 of parts, as will be more fully described, and particularly pointed out in the appended claims.

In the accompanying drawings, Figure 1 is a side elevation of the improved machine. 30 Fig. 2 is a top plan view of the same, a portion of the machine and the leather upon the machine being broken away to show the cutting apparatus. Fig. 3 is a vertical longitudinal section through the machine. Fig. 4 is 35 a vertical transverse section taken on the line $\alpha\alpha$ of Fig. 3.

In the embodiment of the invention illustrated in the drawings the numeral 1 denotes a suitable frame or support having journaled 40 transversely at one end a roller 2, upon which the continuous web or sheet of leather or other material A, to be cut into welts or strips, is wound. From the said roll 2 the leather A passes up over a guide-roller 4, journaled 45 transversely upon the frame 1, in advance of a rotary cutter 5. The said cutter comprises a transversely-journaled shaft 6, upon which intermediate the sides of the frame 1 is a plurality of knives in the form of cutting-disks 7, 50 spaced apart by circular blocks 8. Any num-

ber of said cutting-disks may be provided, and they may be spaced any distance apart, according to the number and size of the welts into which it is desired to cut the sheet of leather. The cutting of the leather is effected 55 by the tension exerted upon the same as it is passed around the cutter, and this tension is produced by providing combined guide and tension rollers 9 and 10 for the leather before it passes to the cutter and a series or group 11 60 of guide and tension rollers after it has been cut into welts or strips B by the cutter. The rollers 9 and 10 are transversely disposed across the frame above and in rear of the cutter, and they are journaled in inclined up- 65 rights 12, secured upon each side of the frame. The web or sheet A of leather after leaving the roller 4 passes under the roller 9, then up over and around the roller 10, and then around the cutter, as seen in Fig. 3. In order to 70 more effectively hold the leather against the cutter while it is being cut, a spring-plate 13, secured upon a cross-bar 14, is adapted to bear upon the leather slightly above the cutter, as shown, and in order to prevent the leather from 75 shifting sidewise a comb-bar 15 is secured transversely to the frame on each side of the cutter. The teeth 16 of these combs project between the cutting-disks 7 to hold the leather against transverse movement, as will be readily understood. The group 11 of transversely-disposed rollers between which the welts B are passed after being formed by the cutter comprises a guide-roller 17, a positively-driven roller 18, and two idler tension-rollers 19 and 80 20, one of the latter being disposed on each side of the positively-driven roller 18. The welts B pass between these rollers, as shown in Fig. 3, and then between one or more groups 21 of separating-rollers. Each one of said groups 85 21 separates one welt or strip B from the body of welts or strips and consists of a positively-driven roller 22 with one tension-roller 23 upon each of its sides. It will be understood that as many of these groups 21 are provided 90 as the number of welts into which it is desired to cut the leather.

In order to drive the cutter, a main shaft 25, which may be driven from any suitable source of power, is journaled in the lower por- 100

tion of the frame 1, and said shaft is geared to the cutter-shaft 6 in any suitable manner, but preferably by an endless belt 26, which is passed about pulleys 27, secured upon said shafts 26 and 6. In order to drive the various other rollers, a transverse shaft 28 is provided and geared to the shaft 25 by a belt 29, passed about pulleys 30, secured to said shafts 25 and 28. The roller 18 is driven by a belt 31, passed about pulleys 32, secured to the shaft 28 and the shaft of the roller 18. The shafts of each two adjacent rollers 22 are geared together by belts 33, passed about suitable pulleys 34, and the shaft of the innermost roller 22 is geared to the shaft 28 by a belt 35, which is passed around pulleys 36, secured to said shafts, as clearly shown in Figs. 1 and 2.

The operation and advantages of the invention will be readily understood from the foregoing description, taken in connection with the accompanying drawings. It will be seen that when the sheet or web of leather is properly placed in the machine, as in Fig. 3, and motion is imparted to the main drive-shaft 25 the cutter and the various rollers will be set in motion through the belt-gearing previously described. The machine may be constructed to cut any number and any size of welts and will work equally well on all kinds, weights, and grades of leather. Owing to the capacity of the machine and the fact that it may be operated by one man, a great saving in time and labor is effected by its use.

It will be understood that various changes in the form, proportion, and the minor details

of construction may be resorted to without departing from the principle or sacrificing any of the advantages of this invention.

Having thus described my invention, what I claim as new, and desire to secure by Letters Patent, is—

1. A welt-cutting machine comprising tension-rollers, a positively-driven roller having a plurality of rotary cutters, spaced apart, means to draw the welts cut by the cutters from the said roller, said means including a positively-driven roller and tension-rollers coacting therewith, and delivery means for the several welts, each of said delivery means including a positively-driven roller and a tension-roller coacting therewith, substantially as described.

2. In a machine of the character described, the combination of a suitable frame, a rotary cutter mounted thereon, tension-rollers adapted to guide the material to be cut, to and from said rotary cutter, a spring adapted to hold said material upon said rotary cutter, and a comb-bar coacting with said rotary cutter to prevent transverse movement of the material upon the said rotary cutter, substantially as described.

In testimony whereof I have hereunto set my hand in presence of two subscribing witnesses.

SAMUEL YEANEY STOCKAMORE.
